UNITED STATES PATENT OFFICE.

EDWARD J. BRIKNER, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

HYDRAULIC TURBINE.

Application filed July 9, 1926. Serial No. 121,299.

This invention relates in general to improvements in hydraulic machines, and relates more specifically to improvements in safety devices for preventing destruction of 5 hydraulic turbines or the like in case of breakage of a portion of the control mechanism thereof.

An object of the invention is to provide simple and efficient means for limiting the 10 travel of the flow controlling guide vanes of a hydraulic machine, in case a portion of the vane actuating mechanism becomes detached or broken.

A clear conception of an embodiment of 15 the invention and of the operation of mechanism constructed in accordance therewith, may be had by referring to the drawing accompanying and forming a part of this specification in which like reference characters 20 designate the same or similar parts in the various views.

Fig. 1 is a central vertical section through a vertical hydraulic turbine of the Francis type, embodying the improved safety 25 appliance.

Fig. 2 is an enlarged fragmentary top view of a portion of the casing and of the actuating ring of the turbine disclosed in Fig. 1.

Fig. 3 is an enlarged fragmentary central vertical section of the turbine, the section being taken through the guide vane actuating mechanism.

Fig. 4 is an elevation of one of the guide vane actuating links and of a fragment of the actuating ring.

The Francis type hydraulic turbine to which the invention has been applied by way of illustration, comprises in general a rotor 2 having a main shaft 3 and formed to receive its supply of actuating fluid from a supply conduit 4 past an annular series of pivotally supported adjustable inlet guide vanes 6. The rotor 2 is housed within a 40 casing comprising a top cover 7, and has its discharge end in communication with a draft tube 5. Each of the adjustable inlet guide vanes 6 has a pivot 8 journaled in the cover 7, and an actuating arm 9 is attached to the upper extremity of each of the vane pivots 8. The pivots 8 are unsymmetrically disposed with respect to the bodies of the vanes 6 and the inlet vane portions are longer than the discharge portions, the former being of 45 sufficient length to strike the rotor 2 if the

vanes are swung completely around. The actuating arms 9 are disposed radially and the inner swinging extremities thereof are pivotally connected to the links 11 by means of pivot pins 13, the opposite ends of the 60 links 11 being pivotally attached to a common adjusting ring 10 by means of pivot pins 14. The adjusting ring 10 is journaled on the casing 7 and the hub of each of the arms 9 is provided with oppositely disposed 65 projections 12 which are so located that they will provide positive stops for the actuating arms 9 of the adjacent vanes 6 as indicated in Fig. 2.

During normal operation of the turbine 70 the fluid under pressure is admitted to the rotor 2 from the supply conduit 4 past the inlet guide vanes 6, and is eventually discharged into the draft tube 5. The guide vanes 6 may be adjusted to vary the inlet 75 opening, by means of a servo-motor of usual construction cooperating with the adjusting ring 10. As the ring 10 by virtue of its bearing upon the turbine casing, is shifted about the axis of the shaft 3, the motion 80 of this ring is transmitted to the guide vanes 6 through the pins 13, 14, the links 11, the arms 9, and the pivots 8 in an obvious manner, causing the vanes 6 to simultaneously swing about their pivotal axes. 85

In case one of the links 11 should break, the corresponding guide vane 6 will tend to tilt or swing freely about its pivotal axis, as shown in Fig. 2, and unless the movement of the released vane is checked, this vane 90 might swing about its pivotal axis to such an extent that the inlet end of the vane would enter the path of the runner 2, whereupon serious damage might result. In order to check the swinging movement of a 95 vane 6 so released, the projections 12 immediately become effective and prevent a released vane 6 from swinging completely about its pivotal axis. It will be apparent that if a released vane should swing in the 100 opposite direction from that indicated in Fig. 2, the projection 12 on the arm 9 of the vane 6 on the opposite side would become effective to limit the swinging movement of the released vane. From the foregoing description it will be apparent that the projections 12 effectively limit the travel of the 105 vane 6, and also permit replacement of a broken link 11 before any serious damage is done. The pins 13, 14 are freely accessible 110

from the exterior of the casing 7 and are readily removable to permit replacement of a link 11 without necessarily stopping the unit.

5 It should be understood that it is not desired to limit the invention to the exact details of construction and operation herein shown and described for various modifications within the scope of the claims may occur to persons skilled in the art.

10 It is claimed and desired to secure by Letters Patent:

1. In combination, a rotor, a plurality of movable guide vanes for controlling the flow 15 of fluid through said rotor, said vanes being located so close to said rotor as to cause interference if permitted to swing freely, a pivot for each of said vanes, an actuating arm secured to each of said pivots, said pivots being spaced equidistant apart and the distance between the axes of successive pivots being greater than the maximum length 20 of one of said arms, an adjusting ring, a link connecting said adjusting ring with each 25 of said arms, and a pair of oppositely disposed projections formed on each of said arms for the purpose of limiting the pivotal

movement of the vanes on opposite sides of said arm so as to prevent interference with said rotor.

2. In combination, a rotor, an annular series of movable guide vanes for controlling the flow of fluid through said rotor, said vanes being located so close to said rotor as to cause interference if permitted to swing freely, a pivot for each of said vanes, an actuating arm secured to each of said pivots and extending inwardly toward the axis of said rotor, said pivots being spaced equidistant apart and the distance between the axes of successive pivots being greater than the maximum length of one of said arms, an adjusting ring, a link connecting the inner end of each of said arms with said adjusting ring, and a pair of oppositely disposed projections on each of said arms whereby said projections on two of said arms will limit the pivotal movement of an intervening arm in opposite directions in case of breakage of the actuating link thereof so as to prevent interference with said rotor.

30 35 40 45 50 In testimony whereof, the signature of the inventor is affixed hereto.

EDWARD J. BRIKNER.
